UNITED STATES PATENT OFFICE.

ETHEL CLEVELAND GALLUP, OF NEW YORK, N. Y.

SELF-STROPPING SAFETY-RAZOR.

1,163,521.

Specification of Letters Patent.

Patented Dec. 7, 1915.

Application filed May 29, 1915. Serial No. 31,155.

To all whom it may concern:

Be it known that I, ETHEL C. GALLUP, a citizen of the United States, and a resident of the city of New York, borough of Manhattan, in the county and State of New York, have invented a new and Improved Self-Stropping Safety-Razor, of which the following is a full, clear, and exact description.

10 This invention relates to safety razors and has particular reference to improved facilities for accommodating a plurality of blades at the same time and for adapting the holder for stropping the blades without 15 removing them from the holder.

More definitely stated, the invention relates to an improved form of safety razor including a head and a handle therefor, one or more razor blade holding devices being 20 permanently connected with the head and adjustable thereon so as to position a blade or blades for either shaving or stropping purposes.

Among the objects of the invention, therefore, is to improve safety razors so as to make them more readily adaptable for either shaving or stropping purposes, without material interchange of parts, than has heretofore been possible.

30 The foregoing and other objects of the invention will hereinafter be more fully described and claimed and illustrated in the drawings forming a part of this specification in which like characters of reference indicate corresponding parts in all the views, and in which—

Figure 1 is a side elevation showing the adaptability of the improvement as a stropping device; Fig. 2 is a vertical longitudinal section of the same; Fig. 3 is a plan view; Fig. 4 is a view corresponding to Fig. 2 but with the parts set for shaving one of the blades and its holding yoke being omitted to better disclose the construction; Fig. 5 is 45 a plan view of the guard mechanism as seen from the line 5—5 of Fig. 4; Fig. 6 is a vertical transverse section on the line 6—6 of Fig. 2; Fig. 7 is a partial side elevation, partial section, on the line 7—7 of Fig. 8; and 50 Fig. 8 is a vertical transverse section on the line 8—8 of Fig. 7.

The several parts of this device may be made of any suitable materials, and the rela-

tive sizes and proportions, as well as the general design of the mechanism, may be 55 varied to a considerable extent without departing from the spirit of the invention hereinafter more fully described and claimed.

Referring more particularly to the drawings, I show a body or head 10 comprising a base 11 and parallel side flanges 12. The base is provided in its center with a socket 13 having an internal thread and counterbored at 14 to receive the upper end of the 65 handle 15. Said end is conical or tapered, as indicated at 16, adjacent which is a thread 17 coöperating with the socket thread, and next adjacent that is a flange 15' fitted slidably in the counterbore 14. Except as 70 stated, the base 11 is flat and smooth on its upper surface where it coöperates with a pair of slidable guard members 19 and 20.

The side flanges 12 of the head are provided with lugs or projections indicated in 75 the nature of inwardly pressed lugs or ribs 21 spaced sufficiently above the base 11 to form keepers or guides for the guard members limiting the movement thereof in a plane close and parallel to the base 11. 80 Each guard member comprises a series of teeth 22 at its upper edge and adjacent each end of each series of teeth there is formed on the guard plate an upwardly and inwardly projecting lip 23. To the inner edge 85 of the guard plate 19 is secured a shank 19' lying in the same plane as the main portion of the guard 19 and having a hole 19^a formed therethrough. The guard plate 20 has an inwardly projecting shank 20' deflected upwardly so as to lie above the shank 19' and also having a hole 20^a. The tapered end 16 of the handle projects through said 90 holes of the shanks, but, as shown best in Fig. 5, the centers of the holes are eccentric to the axis of the handle, and hence, by screwing the handle more or less deeply into the socket, the guard plates will be drawn 95 toward each other proportionally.

I show and employ a plurality of razor blades 24 each having a single cutting edge and having its hilt 24' fitted slidably endwise into a yoke 25 formed preferably of sheet metal and carried upon a shaft 26 extending across the head above the edges of 105 the side flanges 12. A roller 27 extends

through and is journaled in a pair of slots 28 formed in the opposite portions of the flanges 12 and is held parallel to and at a definite distance from the shaft 26 by means of a pair of plates 29 lying preferably just outside of the flanges 12. A pair of intermeshing gear wheels 30 are secured to the ends of the shaft and roller just described. The main portions of the slots 28 are inclined downwardly and outwardly and terminate in upwardly directed seats 28' in which the roller 27 is seated and held by the strop 31 during the stropping operation, and at such time the shaft 26 bears outwardly 10 against a pair of shoulders 32 formed along the upper edges of the flanges 12 whereby the outward swinging movement of the shaft 26 is limited.

The foregoing description of each razor 20 blade and its actuating and holding devices will be understood as being applicable to both of them on opposite ends of the head 18.

The strop 31 is presumed to be anchored at one end as usual and held in the hand at 25 the other, the intermediate portion thereof being threaded through the head beneath the rollers 27 and over a rod or roller 33 extending transversely at the middle portion of the head, but on a line above the plane 30 intersecting the axes of both of the rollers 27 when they are in stropping position. The action of the roller 33 in thus deflecting the intermediate portion of the stropping insures sufficient friction being set up between the strop and the rollers 27 to cause 35 said rollers to turn around their axes and hence cause the rotation of the shafts 26 in the opposite direction through the gears 30. Figs. 1, 2 and 3 indicate the movement of 40 the head relatively toward the left with the result that the blades 24 are caused to drag upon the upper surface of the strop. The blade that is turned inwardly toward the center of the head rests with its edge upon 45 that portion of the strop passing directly over the roller 33. When the end of the stroke is made, and the head is moved in the opposite direction, the friction between the strop and rollers 27 causes them to throw 50 the blades in the opposite direction so as to act upon the opposite faces of the edges in alternation. After the blades are stropped, the head is simply slipped over one end of the strop, and after the strop is out of the 55 way, the rollers 27 are free to drop to or toward the bottoms of the slots 28 along which they may be moved readily by hand so as to permit the edge of the blade to slip beneath the lips 23 of the guards. The 60 guards are then tightened by the action of the handle as above described, so as to cause more or less of the cutting edge of each blade to project as much as the individual operator may desire, and in such position 65 the shafts 26 are held from movement with

relation to the other parts of the device and thereby the blades are held in steady position as shown best in Fig. 4. At 27' is shown a lug bent inwardly from each of the side flanges 12 adjacent the inner edge of 70 the extension or seat 28' of the slot 28, which lug cooperates with the other parts to hold the roller 27 steady while in stropping position. Additional lips 23^a may be formed at the corners of the guard plates which, extending upwardly and inwardly, constitute 75 positive stops limiting the outward movement of the blades.

I claim:—

1. In a safety razor, the combination of a 80 head comprising a pair of parallel side flanges having aligned bearing openings formed therein, a handle having removable threaded connection with the head and having its end projecting between said flanges, a razor blade, a holder for the blade, means controlling the position of the holder and blade including a roller journaled in said aligned openings, and a guard plate movable along the head between said flanges, said guard cooperating with the 85 ends of the blade to hold the same in shaving position and being locked in place by the projecting end of the handle.

2. In a safety razor, the combination of a 90 head comprising a base and a pair of parallel flanges having bearing slots formed therein, a handle cooperating with the base and having its end projecting above the surface thereof, a razor blade, holding means 100 for the blade including a roller journaled in said slots and movable along the same inwardly or outwardly with respect to the axis of the handle, and a guard plate fitted movably against the outer surface of the 105 base and having a shank cooperating with the projecting end of the handle, said guard including means interlocking with the ends of the razor blade to hold it steady in position.

3. In a safety razor, the combination of a 110 body including a base and parallel side flanges, said base having a central socket, a handle secured in the socket and having a tapered end projecting upwardly beyond the upper surface of the base, a pair of guard plates fitted slidably against the outer surface of the base along opposite ends of the head, each guard plate having a shank with a hole therethrough into which the tapered 115 end of the handle extends, the centers of the holes being eccentric to the axis of the handle, a pair of razor blades having their edges cooperating with the guard plates, and means to secure the blades in place.

4. In a safety razor, the combination of a 120 rigid head having parallel side flanges, a pair of guard plates fitted in the head and adjustable longitudinally thereof between the flanges, means extending inwardly from 125

the flanges, confining the guard plates for movement longitudinally of the head only, means to adjust the guards as aforesaid and hold them in adjusted position, a pair of 5 razor blades, means coöperating with the side flanges to position the blades with respect to the head, and interlocking means

between the guard plates and the ends of the blades to lock them in shaving position.
